DESIGN FOR A CLIP BOOKMARK

Edward Leonidas Woodley, Baird, Tex.

Application April 5, 1946, Serial No. 128,328

Term of patent 14 years

(Cl. D6—1)

To all whom it may concern:

Be it known that I, Edward Leonidas Woodley, a citizen of the United States, residing at Baird, in the county of Callahan and State of Texas, have invented a new, original, and ornamental Design for a Clip Bookmark, of which the following is a specification, reference being had to the accompanying drawing, forming a part thereof.

Fig. 1 is a top plan view of a clip bookmark;

Fig. 2 is a plan view of a clip bookmark, showing opposite of Fig. 1; and

Fig. 3 is a side perspective view thereof, showing my new design.

I claim:

The ornamental design for a clip bookmark, as shown.

EDWARD LEONIDAS WOODLEY.
